No. 807,187.

PATENTED DEC. 12, 1905.

G. B. & T. P. MULLEN.
CHAIR SEAT OR BACK.
APPLICATION FILED MAR. 21, 1905.

UNITED STATES PATENT OFFICE.

GEORGE BARTON MULLEN AND TOBIAS PATHRIC MULLEN, OF NEW YORK, N. Y.

CHAIR SEAT OR BACK.

No. 807,187.

Specification of Letters Patent.

Patented Dec. 12, 1905.

Application filed March 21, 1905. Serial No. 251,189.

To all whom it may concern:

Be it known that we, GEORGE BARTON MULLEN and TOBIAS PATHRIC MULLEN, citizens of the United States, and residents of the 5 city of New York, Whitestone, borough of Queens, in the county of Queens and State of New York, have invented a new and Improved Chair Seat or Back, of which the following is a full, clear, and exact description.

Our invention relates to chairs and analogous furniture, our more particular object being to provide a removable member which may be used either as a seat or as a back and furnishing certain constructional advantages 15 hereinafter described.

Reference is to be had to the accompanying drawings, forming a part of this specification, in which similar characters of reference indicate corresponding parts in all the figures.

Figure 1 is a fragmentary perspective view 20 of a chair equipped with our invention. Fig. 2 is a central vertical section through the same. Fig. 3 is a fragmentary central section through the seat of another chair equipped 25 with another form of our invention, and Fig. 4 is a perspective detail of the seat-frame.

The frame of the chair-seat is shown at 5, and the frame of the chair-back at 6. At 78 are two removable plates substantially similar 30 in design. The plate 7 is let into the frame 5 by means of a step 9, as indicated in Fig. 2. The plate 8 is similarly let into the frame 6 in the back of the chair by means of a step 10. The plates 7 and 8 are provided with large 35 apertures 11, into each of which is fitted a frame 12, over which is stretched a binding-cloth 13 and an outer wearing-cloth 14. Screws 15 connect the frames 12 with the plates 7 and 8 and are secured upon the inside 40 by means of nuts 16. Projecting inwardly from each frame 12 is a continuous flange 17, provided with holes 18 for the purpose of mounting upon the flange a cane or wicker-work bottom, which may be employed 45 instead of the outer wearing-cloth 14 and the lining 13, if desired.

In the form shown in Fig. 3 the seat-frame appears at 19, and fitting snugly into it is a plate 20, provided with a beveled flange 21. 50 Mounted within the frame 20 and fitting the same snugly is a rectangular frame 25, which supports a cane or wicker-work bottom 26.

This bottom is connected with the frame 25 by means of the flange 27, provided for the purpose. Screw-bolts 23, provided with nuts 55 24, pass through the frames 20 and 25, thereby sustaining the frame last mentioned in position. The purpose of beveling the flange 21 is to provide the plate 20 with a portion projecting over the seat-frame 19, so as to give 60 the plate 20 a solid support and yet avoid the occurrence of sharp angles upon the chair-seat.

A chair constructed as above described possesses great strength. The bolts or screws 65 15 hold firmly together the parts which they engage, and the plates 7, 8, and 20 serve as corner-braces for the surrounding parts.

Having thus described our invention, we claim as new and desire to secure by Letters 70 Patent—

1. In a device of the character described, the combination of a plate provided with a central aperture, and also provided with a beveled flange projecting outwardly therefrom and with a flange projecting inwardly 75 therefrom, a seat portion connected with said flange thus projecting inwardly, and a seat-frame encircling said plate.

2. The combination of a rectangular seat-frame, provided with a central aperture, a plate mounted within said central aperture and provided with a beveled flange extending outwardly therefrom, said beveled flange resting upon said seat-frame, a second frame 85 mounted within said frame first mentioned, and bolts for connecting said frames together.

3. The combination of a seat-frame provided with a central aperture, a plate provided with a beveled flange and disposed within said seat-frame, said beveled flange projecting over a portion of said seat-frame, said plate being provided with a central aperture, and a member mounted within said central aperture for supporting a bottom of wicker-work 95 or the like.

In testimony whereof we have signed our names to this specification in the presence of two subscribing witnesses.

GEORGE BARTON MULLEN.
TOBIAS PATHRIC MULLEN.
